UNITED STATES PATENT OFFICE.

EDGAR M. BENHAM, OF NORWOOD, OHIO, ASSIGNOR, BY MESNE ASSIGNMENTS, TO THE MOSLER LOCK COMPANY, OF CINCINNATI, OHIO, A CORPORATION OF OHIO.

COMBINATION-LOCK.

1,345,574.

Specification of Letters Patent.

Patented July 6, 1920.

Application filed July 23, 1917. Serial No. 182,182.

To all whom it may concern:

Be it known that I, EDGAR M. BENHAM, a citizen of the United States, residing at Norwood, in the county of Hamilton and State of Ohio, have invented new and useful Improvements in Combination-Locks, of which the following is a specification.

My invention relates to "permutation" or "combination" locks; its object being to simplify and improve the system of underlying principles of structure and operation, and produce a superior safety lock adapted to an almost unlimited range of combination settings which may be easily and quickly changed as desired, and operated by direct single movements of the dial to the successive numbers without the multiplied intermediate revolutions heretofore necessary in tumbler locks. Thus, not only is the manual working much simplified but the necessity of carrying in the mind a somewhat complicated system of movements entirely avoided.

The details of structure and of movement whereby these results are accomplished will more fully appear in the following specification, in connection with the accompanying drawings illustrating a preferred form of my invention.

In the drawings,

Figure 1 is a face view of the tumbler system carried upon the stump of the primary drive wheel detached from the dial arbor.

Fig. 2 a side elevation of the same system shown in position upon the stump of the primary drive wheel in connection with the auxiliary drive wheel carried upon the dial arbor;

Fig. 3 a face view, and Fig. 4 an elevation in axial section of the primary drive wheel detached;

Fig. 5 a face view and corresponding axial section of one of the enlarged friction washers detached; and

Fig. 6 a face view and corresponding edge elevation of one of the fingers or pawls used with each tumbler.

Referring to the drawings A^1 designates the primary drive wheel carried loosely on the arbor c of the dial C , and having an extended hub or "stump" a on which are carried the tumblers or disks, b^1 b^2 b^3 forming a nest or system operating in connection with the primary drive-wheel A^1 and an

auxiliary drive wheel A^2 adjacent thereto, the latter being fixedly but removably secured (as by a key c^1) upon the dial arbor c and having a laterally projecting lug a^2 entering a segmental slot a^1 in the drive 60 wheel A^1 .

The disks are unitary and are duplicates one of another, placed consecutively adjacent, each provided with a peripheral slot s corresponding with similar slots s^1 s^2 in 65 the primary and auxiliary drive wheels A^1 A^2 respectively. Each disk is toothed around its entire periphery and numbered clockwise (excepting for the vacant spaces of the slots s)—the teeth being spaced apart 70 correspondingly with the unit marks upon the dial C continuously from 1 to 100—the starting point being the center of the slot s .

With each of the disks excepting the first (which has but one) is associated two radial 75 fingers or pawls d , duplicates, each formed as shown in Fig. 6, with a loop to embrace the stump a and extended radially beyond the periphery of the disk with its projecting terminal bent forward and downward—as 80 at d' —and notched at its end to fit over and engage one of the peripheral teeth of the disk. The two fingers or pawls d are placed side by side at the rear side of the disk and between these and the face of the 85 next disk is placed an enlarged friction washer E (shown in Fig. 5) of equal diameter with the drive wheels A^1 A^2 and somewhat larger than the disks. The friction washers are provided each with a peripheral 90 slot s^2 and are centered upon the stump a of the drive wheel A^1 and are prevented from inter-rotation thereon by projections e fitting in opposite side grooves a^3 of the stump a . The peripheral surfaces of the 95 drive wheels A^1 A^2 and of the friction washers E present a smooth riding-surface for the angle-bar F , out of actual contact with the disks. The angle-bar also serves as an arresting stop for the rotative movement 100 of the disks by contact with the radially projecting fingers or pawls d . It may now be explained that the segmental opening a^1 of the primary drive wheel A^1 in which operates the lateral projection a^2 of the auxiliary drive wheel A^2 is arranged as shown in the body of the drive wheel diametrically opposite to the peripheral slot s^1 , and is of sufficient length to allow a lost motion a trifle in excess of the width of the 110

peripheral slots s^1 s^2 . By this construction the primary drive wheel A^1 lags behind the auxiliary drive wheel A^2 so that at no time do the peripheral slots s^1 s^2 register except in the last movement of working the combination, to be indicated later. The special purpose here, is to keep the angle bar from touching any disk peripherally while the combination is being run.

10 It will be seen that the rotation of the dial C and its arbor c carries all the disks in unison through the co-action of the auxiliary drive wheel A^2 and the primary drive wheel A^1 upon whose stump the disks are mounted, and the frictional engagement of the positively-driven friction washers E with the disks.

But, one after another, the rotation of the disks is arrested by contact of their pawl tips with the angle-bar F,—at one side or the other, according to the direction of rotation—each disk being rotated independently and not by a movement communicated through and by the disk series. Each one is also independently arrested by contact of its pawl fingers with the angle bar.

In setting to a new combination, the auxiliary drive wheel A^2 is removed from the dial arbor and the primary drive wheel 30 A^1 together with its nest of disks intact is taken off the stump a for convenience, and the disks arranged with the slots s and s^1 in line.

Then, while preserving the slot-alinement, 35 the finger pawls of each in turn are disengaged and reset by rotating the disk until the desired number appears in the slot vacancy of the disk in front, and engaging the pawl anew and moving the disk to bring 40 its slot back to alinement, and so to the next.

The elements of the combination selected should be at least five numbers apart and the first should be between 20 and 80.

45 The mode of operation is as follows:

The "setting" of the disks to respond to given numbers is by adjustment of the pawls, as one sets the hands of a clock, to the given dial numbers reproduced thereon, 50 and secure the same in proper engagement with the disk teeth. The first disk (nearest the drive wheels) carries but one pawl, while the others (two in the present illustration) carry two pawls each, which, for convenience, we may designate "primary" and "secondary". The disks being held as described, each independently of the others, by frictional engagement upon the stump of the primary drive wheel, all rotate with it 55 as the dial is rotated, until one or another is caught and held temporarily against rotation by contact of its pawl-terminal (primary or secondary, according to the direction of rotation) with the angle bar.

60 In selecting numbers for combination I

make allowance for the aggregated lost motion, (1) of the slot-connection between the primary and secondary drive wheels; (2) the width of the angle bar; and (3) the width of one pawl, which, together, constitute a circumferential space,—for example, of ten unit markings,—being five on each side of zero; so that the highest number available for a combination will be 95, and the lowest 5. Supposing the combination to be 80—85—65—94, (94 being a fixed number for all combinations) the pawl of No. 1 disk is set at 80; the primary pawl of No. 2 disk at 85 and its secondary at a number less than 80 and greater than 65—say 70; 80 and the primary of No. 3 disk at 65, and its secondary at a number greater than 85—say 95. Thus the angle formed by the pawls of No. 2 disk is within that formed by those of No. 3 disk, and the pawl of No. 1 disk is within this smaller angle.

(1) If now the dial be turned to the left the primary pawl of No. 3 disk is first arrested and No. 3 disk held against further rotation by the angle bar; but, continuing 90 the rotation, the secondary pawl of No. 2 disk is in the same manner arrested and its disk held against rotation; and on registering 80, the pawl of No. 1 disk is in like manner arrested and its slot alined with the slot 95 in the primary drive wheel.

(2) The next dial movement is to the right, resulting in the arrest first of the secondary pawl of No. 3 disk next, of the primary pawl of No. 2 disk, and upon registering 85, the slots of No. 1 and No. 3 disks 100 will be alined with the primary drive wheel.

(3) The dial movement is next to the left to the dial number 65, arresting the primary pawl of disk No. 3, which alines its slots with 105 the other previously alined, thus bringing all the slots in alinement.

(4) A reversal of rotation of the dial to the right to 94, (the fixed number), brings the slot of the primary drive wheel in line 110 with the angle bar with which the disks are already alined; and a slight motion toward zero (to take up the lost motion between the drive wheels) lines the secondary drive wheel with the first and allows the angle bar 115 to fall into the alined slots.

Thus the principle of the invention may be said to reside in the inventive idea of a series, or system of tumblers consisting of toothed disks, carried loosely upon the 120 stump of a drive wheel embracing the dial arbor, and rotated by frictional engagement with said stump independently of each other; and the provision of primary and secondary radial adjustable pawls (one only 125 for the first in series) secured upon the disks and arranged at successively enlarging angles in the series relation of the disks and adapted to be independently arrested by contact with the angle bar by successively 130

reversed movements of the dial. It resides also in part in the constructive features and arrangement of the parts contributing to the general results accomplished.

5 The present illustration comprehends a system of three disks, but a greater number may be used and the range of possible combinations thereby be increased without departing from the principle involved.

10 I claim as my invention and desire to secure by Letters Patent of the United States:—

15 1. A combination lock embodying a rotatable dial arbor; a drive-wheel removably secured thereon; a second drive-wheel interconnected with the first, loosely mounted on the arbor and provided with an extended hub; a system of toothed disks or tumblers independently carried rotatably upon said 20 stump, and each provided with one or more radial pawls, circumferentially adjustable in relation thereto; and an angle bar extended across said drive-wheels and disks in the rotative path of the projecting extremities of said pawls as an arresting stop; said drive-wheels and disks being peripherally slotted to receive the angle-bar.

25 2. In a combination lock of the character indicated, a dial arbor; a peripherally slotted drive-wheel having an extended hub loosely seated on said arbor; a plurality of peripherally slotted and notched disks of a slightly less diameter than the drive-wheel and carried loosely on said hub but frictionally engaged therewith in rotation; and a fence or angle-bar extended across said disks and drive-wheel and resting by gravity on the latter.

30 3. In a combination lock of the character indicated, a dial arbor; a slotted drive wheel with extended hub; the nest of disks on said hub; and a second drive-wheel secured fixedly on the dial arbor adjacent to the first and loosely interconnected therewith in rotation to permit the first drive wheel to lag behind sufficiently to prevent alinement of the drive-wheels until all the disks are alined.

35 4. In a combination lock of the character

indicated, the combination of a dial arbor; 50 a drive-wheel or tumbler with extended hub carried loosely thereon and adapted to carry on its hub a nest of disk tumblers; and a second drive-wheel or tumbler carried fixedly on the said dial arbor outwardly adjacent to the first drive-wheel or tumbler as a holder, and interconnected therewith for rotation.

55 5. In a tumbler lock of the character indicated, a dial arbor; a slotted drive-wheel with extended hub, loosely mounted thereon; a plurality of independent notched and slotted tumbler-disks carried loosely on said hub; a corresponding series of friction washers of the same diameter as the drive-wheel non-rotatively seated on said hub between the tumbler disks; and a second drive-wheel fixed on said dial arbor outwardly adjacent to the first drive wheel and interconnected therewith for rotation.

60 6. In a combination lock of the character indicated, the combination of a dial arbor; an auxiliary drive wheel seated fixedly upon the said arbor and having a peripheral slot; a primary drive wheel having a peripheral slot and an extended hub and carried loosely upon the said arbor in driving relation with the auxiliary drive-wheel; a plurality of disk-tumblers each having a peripheral slot and carried loosely on said stump, provided 65 with radial pawls extending outward beyond the peripheries and adjustable to normally fixed relation therewith; a corresponding series of frictional washers, each having a peripheral slot and carried in 70 fixed rotative connection with the stump with the peripheral slots in alinement with that of the primary drive-wheel, said washers being severally arranged in frictional contact with said disk-tumblers; and an 75 angle bar extending across and riding upon the friction washers and drive-wheels out of contact with the disk-tumblers, in the path of the radially extended pawls.

80 In testimony whereof I have hereunto set 85 my hand.

EDGAR M. BENHAM.
